(57) CLAIM

The ornamental design for a sandal, as shown and described.

DESCRIPTION

2 Sandal

2.1 is a perspective view of a sandal showing my new design;

2.2 is a front view thereof;

2.3 is a back view thereof;

2.4 is a right side view thereof;

2.5 is a left side view thereof;

2.6 is a top view thereof; and

2.7 is a bottom view thereof;

The broken line showing of a sole is for the purpose of depicting portions of a sandal and forms no part of the claim.
